US0D1032975S

(12) **United States Design Patent** (10) Patent No.: **US D1,032,975 S**
(45) Date of Patent: ** *Jun. 25, 2024

(54) **VACUUM CLEANER**

(71) Applicant: **SharkNinja Operating, LLC**,
Needham, MA (US)

(72) Inventors: **Scott B. Niedzwecki**, East Walpole,
MA (US); **Junghwan Chei**, Chestnut
Hill, MA (US)

(73) Assignee: **SHARKNINJA OPERATING LLC**,
Needham, MA (US)

(*) Notice: This patent is subject to a terminal disclaimer.

(**) Term: **15 Years**

(21) Appl. No.: **29/696,416**

(22) Filed: **Jun. 27, 2019**

(51) LOC (14) Cl. **15-05**

(52) U.S. Cl. **D32/22**

CLAIM

The ornamental design for a vacuum cleaner, as shown and described.

DESCRIPTION

FIG. 1 is a front view of a vacuum cleaner, showing the new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a front, top left perspective view thereof;

FIG. 8 is a front, bottom left perspective view thereof;

FIG. 9 is a rear, top right perspective view thereof;

FIG. 10 is a rear, bottom, right perspective view thereof;

FIG. 11 is another front, top left perspective view thereof;

FIG. 12 is another front, bottom, left perspective view thereof;

FIG. 13 is a front, top, right perspective view thereof; and,

FIG. 14 is a front, bottom, right perspective view thereof.

The broken lines in the figures show portions of the vacuum cleaner that form no part of the claimed design.
